Primary Examiner — Sandra S Snapp*Assistant Examiner* — Katherine Glennon(74) *Attorney, Agent, or Firm* — Abelman, Frayne & Schwab(57) **CLAIM**

The ornamental design for a watch, as shown and described.

DESCRIPTION

FIG. 1 is a front view of a watch showing the new design; FIG. 2 is a rear view thereof; FIG. 3 is right side view thereof; FIG. 4 is a left side view thereof; FIG. 5 is a top view thereof; FIG. 6 is a bottom view thereof; FIG. 7 is a front, right, and top perspective view thereof; and, FIG. 8 is a rear, left, and top perspective view thereof. The broken line showing of the watch is for the purpose of illustrating portions of the article and forms no part of the claimed design.

1 Claim, 6 Drawing Sheets(56)
